HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

PAPER-EJECTING MECHANISM.

1,148,509.

Specification of Letters Patent. Patented Aug. 3, 1915.

Application filed June 16, 1914. Serial No. 845,485.

To all whom it may concern:

Be it known that I, HARRY C. GAMMETER, a citizen of the United States, residing at Cleveland, in the county of Cuyahoga and 5 State of Ohio, have invented a certain new and useful Improvement in Paper-Ejecting Mechanism, of which the following is a full, clear, and exact description, reference being had to the accompanying drawings.

10 The object of this invention is to provide a simple and effective device for ejecting or delivering the paper from small rotary printing machines, for example, such machines as carry individual type and may be 15 operated by hand for office use.

The invention is hereinafter more fully described and the essential characteristics are set out in the claims.

In the drawings, Figure 1 is an end view, 20 partly broken away, of my ejecting mechanism in place in a rotary printing machine which is shown somewhat diagrammatically;; Fig. 2 is a plan of a portion of such printing machine just above the platen and 25 ejecting mechanism, this view showing a sheet of paper passing through the machine; Fig. 3 is a perspective view on an enlarged scale of the ejecting mechanism proper.

As shown in Fig. 1, 1 represents the frame 30 of the machine, 2 a rotary printing drum, 3 a coacting rotary platen, 4 a fountain inking roller, 5 a form roller contacting with the fountain roller and with the drum, and 35 6 and 7 suitable feeding rollers. These parts may be of any well-known construction.

Connected with the platen 3 is a gear 10 which may coact with a gear on the drum (not shown) for driving the platen. This 40 gear also meshes with an idler 11 carried by the frame 1, which idler meshes with a gear 12 on the shaft of an ejector roller 13. This roller is therefore continuously rotated, when the drum is rotated, in a direction to 45 deliver the printed sheet A, as indicated by arrows in Fig. 1.

Slidably mounted on a cross rod 20 are arms 21 carrying rollers 22 designed to rest on and coact with the roller 13. Each arm 50 21 is preferably a sheet metal member having a top plate and side plates 23 bent at right angles thereto and provided with eyes 24 which surround the rod 20 and may shift the rollers 22 laterally, as desired, while 55 always in position to coact with the roller 13.

The rollers 22 are held in coaction with the roller 13 by a coiled spring 27 between the ears 23, this spring having one end 28 overhanging and bearing downwardly on the top of the arm 21 and the other end 60 turned upwardly into a longitudinal groove 29 along the under side of the rod 20. This construction, while enabling the arm to be shifted laterally, as desired, maintains, a spring action to cause the roller 22 to bear 65 on the roller 13.

30 indicates a pair of flat strippers which extend between the drum and platen near the opposite ends of the drum and lie above the paper and operate to strip it from the 70 drum after it has passed the line of printing impression. These strippers are shown as sheet metal strips having bent forward ends 32 which loosely embrace a stationary cross rod 33. At their rear ends the strips 75 have upward side flanges 35 which have eyes surrounding the rod 20. The flanges 35 start at some distance in advance of the rollers 22 and an opening 37 is made through the bottom of the strip at this roller so that 80 it may act on the roller 13.

It will be seen that the construction is extremely simple. It is effective in stripping the paper from the printing drum and directing it to the ejector rollers 13 and 22, 85 which deliver it at the rear of the machine. The positioning of the strippers beyond the printed page while over the margin of the paper automatically positions the ejector rollers 22 so that there is no danger of their 90 engaging the printing surface. This insures the delivery of a clean copy.

Having thus described my invention, what I claim is:

1. The combination, with a printing device, of a delivery roll, an ejector roll adapted to coact therewith, an arm carrying the ejector roll, a rod on which the arm is pivotally and slidably mounted, and a spring acting on the arm irrespective of its lateral 100 position.

2. The combination, with a printing device, of a delivery roll, an ejector roll adapted to coact therewith, an arm carrying the ejector roll, said arm consisting of a plate 105 flanged at its edges to form a support for the roll and having eyes at its rear to surround a stationary rod, and a spring surrounding the rod between the eyes and acting on the arm, said spring having one end 110

- extending over the intermediate portion of the arm and the other end turned into a longitudinal groove in the rod, whereby the arm and roller are adjustable on the rod 5 and the spring constantly effective.
3. The combination, with a printing couple, of a stripping device extending between the members of the couple, a delivery roll, a shiftable roller adapted to coact therewith, and a connection between said shiftable roller and the stripper whereby they may be concurrently positioned.
4. The combination, with a rotary printing couple, of a flat strip extending between the two, a rod parallel with the couple, an arm adjustable along said rod, a roller carried by said arm, and a connection between the flat strip and the arm for simultaneous adjustment.
5. The combination, with a rotary printing couple, of a flat strip extending between the two, a rod parallel with the couple, an arm adjustable along said rod, and a roller carried by said arm, said strip being flanged 20 at its rear portion to extend alongside of the arm and embrace the rod.
6. The combination, with a printing couple, of a rod parallel therewith, an arm slidably mounted on the rod and carrying 25 a roller, a roller with which the roller first mentioned coacts, and a strip extending between the members of the couple and flanged at its rear portion and provided with eyes extending around the rod.
7. The combination, with a printing couple, of a rod parallel therewith, an arm slidably mounted on the rod and carrying a roller, a roller with which the roller first mentioned coacts, and a strip extending 30 between the members of the couple and flanged at its rear portion on opposite sides of the arm and provided with eyes extending around the rod, said strip having an opening through which the roller on the arm 35 acts.
8. The combination, with a printing couple, of a delivery roll, an ejector roll adapted to coact therewith, an arm carrying the ejector roll, said arm consisting of a plate flanged at its edges to form a support 40
- for the roll and having eyes at its rear to surround a stationary rod, a spring surrounding the rod between the eyes and acting on the arm, said spring having one end extending over the intermediate portion of the arm and the other end turned into a longitudinal groove in the rod, and a stripper extending between the members of the couple and embracing the arm and having eyes surrounding the rod. 45
9. The combination, with a rotary printing couple, of a laterally shiftable flat strip extending between the two, a rod parallel with the couple, said strip being flanged at one end and provided with eyes to embrace the rod slidably, said strip having a hook at its other end, and a rod which said hook slidably embraces. 50
10. The combination, with a printing couple, of a rod parallel therewith, an arm slidably mounted on the rod and carrying a roller, a roller with which the roller first mentioned coacts, a strip extending between the members of the couple and flanged at its rear portion on opposite sides of the arm and provided with eyes extending around the rod, the forward end of said strip being bent backwardly in a U-shape, and a rod carrying such forward end. 55
11. The combination of a rotary printing couple, a pair of strips extending between the members of the couple, a rod in front of the couple carrying the forward end of the strips, a paper feeding device at the front of the couple beneath such forward ends of the strips, a rod at the rear of the couple, a delivery roller at the rear of the couple, arms slidably mounted on said rod and carrying rolls resting on and coacting with the delivery rollers, the rear ends of said strips being flanged upwardly onto opposite sides of the arm and provided with eyes extending around the rod. 60

In testimony whereof, I hereunto affix my signature in the presence of two witnesses.

HARRY C. GAMMETER.
